QUATERNARY AMMONIUM SALTS AND
PROCESS OF PREPARING THEM

Gerhard Balle, Frankfort-on-the-Main, Johann Rosenbach, Wiesbaden, and Ludwig Orthner, Frankfort-on-the-Main, Germany, assignors, by mesne assignments, to General Aniline & Film Corporation, New York, N. Y., a corporation of Delaware

No Drawing. Application May 11, 1939, Serial No. 273,042. In Germany May 14, 1938

2 Claims. (Cl. 260—295)

1

The present invention relates to quaternary ammonium salts and to a process of preparing them.

We have found that valuable quaternary ammonium salts are obtainable by converting ester-like constituted compounds having the formula $R-X-CH_2-OCOR_2-Hal$ wherein R stands for an aliphatic, aliphatic-cycloaliphatic or araliphatic radical of at least 12 carbon atoms which may be interrupted by heteroatoms; X means oxygen or sulfur; R_2 represents a low molecular aliphatic hydrocarbon radical which may be substituted by halogen, and Hal means halogen into quaternary ammonium salts. This conversion into quaternary ammonium salts is carried out by causing the starting materials corresponding with the above-indicated formula to react with tertiary aliphatic or heterocyclic bases.

The ester-like constituted compounds of the above-indicated formulae used as starting materials are prepared according to the process of U. S. Patent No. 2,283,764, issued May 19, 1942, for "Ester-like condensation products and a process of preparing them" in the name of Johann Rosenbach and Gerhard Balle.

Halogen-substituted esters which may be used as starting materials for the present invention are, for instance: the products of the reaction of salts of chloracetic acid, dichloracetic acid, bromoacetic acid, alpha- or beta-chloropropionic acid with halogen-methyl ethers of mono- or polyhydric alcohols, such as dodecanols, octadecanols, oleyl alcohol, montan alcohols, resin alcohols and the hydrogenation products thereof, octadecane-diol, dichlorooctadecane-diol, octadecyl-monoglycol ether, para-butylphenyl-butanol, octadecylphenylglycol ether, naphthene alcohols. The corresponding halogen-methyl compounds may be made, for instance, as described in British specification No. 394,196.

Furthermore, there may be named the ester-like constituted compounds prepared by the reaction of salts of halogenated acids with the halogen-methyl compounds of mono- or polyhydric mercaptans, such as dodecylmercaptan, octadecylmercaptan, which may be produced in a manner analogous to that of the halogen-methyl ethers already named.

There are also suitable the products obtainable from salts of the above-mentioned halogenated acids and from the halogen-methyl compounds of carboxylic acid amides or carbamic acid esters, for instance, lauric acid amide, stearic acid amide, oleic acid amide, acetic acid-N-octadecyl-amide, butyric acid-N-dodecyl amide, stearic acid methylamide, montanic acid amide, resinic acid amides, the amides of the carboxylic acids ob-

2

tainable by oxidation of paraffin or by similar processes which have at least 12 carbon atoms, furthermore, dichlorostearic acid amide, ricinoleic acid methylamide, iso-octylphenoxyacetic acid amide, isododecylcyclohexyl-oxyacetic acid amide, tributylphenylacetic acid-N-butylamide, para-butylphenylbutyric acid amide, carbamic acid dodecyl ester, N-methylcarbamic acid octadecyl ester, carbamic acid iso-dodecyl phenyl ester, N-methylcarbamic acid iso-dodecylcyclohexylglycol ester. The corresponding halogen-methyl compounds may be prepared, for instance, as described in French Patents Nos. 818,438, and 819,945.

Besides there are appropriate the reaction products of the salts of halogenated carboxylic acids with halogen-methyl compounds obtainable by causing a compound having at least 12 carbon atoms and containing nitrilo-group to react with formaldehyde in the presence of hydrogen halide.

Of esters containing basic nitrogen which may be transformed into quaternary ammonium salts, there may be named, for instance, the ester-like compounds obtained by reaction of the above-named halogen-methyl compounds with salts of dimethylamino-acetic acid, piperidino-acetic acid, alpha- and beta-diethylaminopropionic acid.

The procedure is the following: The mixture of the two reaction components necessary for the preparation of the ammonium salts is heated for a short time or it is allowed to stand for a prolonged time at ordinary temperature the simultaneous application of a solvent being advantageous in some cases. The product precipitates in most cases in a crystalline form and is separated from the solvent.

The quaternary ammonium salts thus produced correspond with the general formula

wherein R, R_2 and X have the above-indicated meaning, Hal means a halogen atom and Z means that at the pentavalent nitrogen atom three aliphatic hydrocarbon radicals are attached or that this nitrogen atom is the member of an unsaturated heterocyclic ring system or the member of a saturated heterocyclic ring system in which latter case still an aliphatic hydrocarbon radical is bound at the nitrogen atom.

The new products are generally solid bodies which are soluble or capable of being dispersed in water and may be used in the textile industry for rendering fibrous material water-repellant in which case it is necessary to subject the im-

pregnated textile material to a heat-treatment. They may be used either per se or in admixture with other products having a similar action, such as fatty alcohol sulfonates, fatty acid condensation products, alkylated naphthalenesulfonic acids or the like.

The following examples serve to illustrate the invention, but they are not intended to limit it thereto; the parts are by weight:

(1) 25 parts of the product of the reaction of dodecyl-chloromethyl ether and sodium chloracetate are heated to boiling for 1 hour with 15 parts of dimethylamino-ethyl-methyl ether and 150 parts of benzene. The solvent is then eliminated at 50° C. to 60° C. under reduced pressure. The residue forms a soft, brownish mass which gives with water clear, well-foaming solutions.

(2) 150 parts of the product of the reaction of hexadecyl-chloromethyl ether with sodium chloracetate are dissolved in 350 parts of pyridine. The mixture is allowed to stand for about 3 days at ordinary temperature, the precipitated crystalline mass is filtered with suction and washed with acetone. The compound obtained is a feebly colored body which is soluble in water to a clear solution.

(3) A solution of 20 parts of trimethylamine in 150 parts of benzene is mixed with a mixture of 40 parts of the ester prepared from octadecyl-chloromethyl ether and sodium chloracetate, and 100 parts of benzene. The whole is allowed to stand at ordinary temperature for about 40 hours, the precipitated product is filtered with suction and subsequently washed with benzene. The compound is a colorless body which is readily soluble in water.

(4) 308 parts of the ester obtained from octadecyl-chloromethyl ether and sodium chloracetate are dissolved, while gently heating, in 175 parts of pyridine and allowed to stand for 3 days at ordinary temperature. The crystalline mass obtained is stirred with acetone, filtered with suction and washed with acetone. The brownish product dissolves in hot water to a clear solution.

(5) 30 parts of the product of reaction of dodecyl-chloromethyl sulfide and sodium alpha-chloropropionate are boiled for some time together with 15 parts of dimethylamino-ethyl-methyl ether and 200 parts of benzene. The benzene is then distilled at 50° C. under reduced pressure.

(6) 52 parts of the product obtained from stearic acid chloromethylamide and sodium chloracetate are dissolved, while gently heating, in 140 parts of pyridine and the mixture is allowed to stand for some days. When the crystallisation is complete the whole is filtered with suction and washed with acetone. A nearly colorless body remains on the filter which dissolves in hot water.

(7) 60 parts of the reaction product obtained from the chloromethyl compound of carbamic acid octadecyl ester and sodium chloracetate are

mixed with 150 parts of pyridine and the precipitated crystalline mass is filtered with suction after 3 days' standing. In order to remove the excess of pyridine it is washed with acetone. A brownish product is obtained which dissolves in water to a clear solution.

(8) 25 parts of the substance obtained from octadecyl-chloromethyl ether and sodium dimethyl-aminoacetate are dissolved in 30 parts of ethylene chlorhydrin and the mixture is allowed to stand for 3 days at ordinary temperature. The precipitated colorless crystalline mass is filtered with suction and dried at 30° C. under reduced pressure.

(9) 80 parts of an ester of the formula $C_{18}H_{37}OCH_2O.CO.CHCl_2$ are dissolved in 100 parts of benzene and 16 parts of pyridine are added. The whole is allowed to stand for 3 days at room temperature. Then the benzene is distilled under reduced pressure. There remains a feebly brown colored product which dissolves in water to a clear solution. The ester used as starting material is obtainable by condensing octadecyl-chloromethyl ether with sodium dichloroacetate.

We claim:

1. The process of preparing quaternary ammonium salts which comprises reacting an ester-like constituted compound of the general formula

wherein R stands for a radical of at least 12 carbon atoms selected from the group consisting of aliphatic, aliphatic-cycloaliphatic, and araliphatic radicals which radicals are interrupted by hetero atoms in their carbon structures, X stands for a member of the group consisting of oxygen and sulfur, R₂ stands for a member of the group consisting of low molecular aliphatic hydrocarbon radicals and low molecular aliphatic hydrocarbon radicals substituted by halogen, and Hal means halogen with a tertiary base of the group consisting of aliphatic and heterocyclic bases.

2. The quaternary ammonium salts of the general formula:

wherein R stands for a radical of at least 12 carbon atoms selected from the group consisting of aliphatic, aliphatic-cycloaliphatic, and araliphatic radicals which radicals are interrupted by hetero atoms in their carbon structures, X stands for a member of the group consisting of oxygen and sulfur, R₂ stands for a member of the group consisting of low molecular aliphatic hydrocarbon radicals and low molecular aliphatic hydrocarbon radicals substituted by halogen, Hal means halogen, and N≡Z stands for a member of the group consisting of tertiary aliphatic amines and tertiary heterocyclic bases.
